United States Patent Office

Des. 177,360
Patented Apr. 10, 1956

177,360

BROILER PAN

Donald Becker and Elihu Tchack, Livingston, N. J.

Application December 23, 1954, Serial No. 33,661

Term of patent 14 years

(Cl. D44—1)

Fig. 1

Fig. 2

Fig. 3

Fig. 4

Fig. 5

Figure 1 is a perspective view of a broiler pan showing our new design;

Figure 2 is a side view thereof;

Figure 3 is an end view thereof;

Figure 4 is a sectional view taken along line 4—4 of Figure 1; and

Figure 5 is a sectional view taken along line 5—5 of Figure 1.

We claim:

The ornamental design for a broiler pan, substantially as shown.
